UNITED STATES PATENT OFFICE

IRA H. OBERNDORFER, OF BROOKLYN, NEW YORK

DESIGN FOR PAJAMAS

Application filed February 23, 1932. Serial No. 42,957. Term of patent 7 years.

To all whom it may concern:

Be it known that I, IRA H. OBERNDORFER, a citizen of the United States, and a resident of New York, borough of Brooklyn, in the county of Kings and State of New York, have invented the new, original, and ornamental Design for Pajamas, of which the following is a specification.

Reference is had to the accompanying drawings, forming part thereof, wherein—

Figure 1 is a front perspective view of a pair of pajamas showing my new design, the rear part of the pajamas being plain except for the cuffs around the sleeves, the lower

ends of the pants and the collar, which are uniform in appearance throughout.

Figure 2 is an enlarged fragmentary view of part of the belt formation illustrating the detail formation of the ornamental member at the front.

The dominating feature of my design is the sash or belt effect at the top of the pants section.

I claim:

The ornamental design for pajamas substantially as shown and described.

IRA H. OBERNDORFER.
